BY *Albert L. Bissell*

ATTORNEY

UNITED STATES PATENT OFFICE.

HECTOR P. MACLAGAN, OF PARK RIDGE, ILLINOIS, ASSIGNOR TO McINTOSH BATTERY AND OPTICAL CO., OF CHICAGO, ILLINOIS, A CORPORATION OF ILLINOIS.

X-RAY CONE.

1,352,198.

Specification of Letters Patent. Patented Sept. 7, 1920.

Application filed September 21, 1918. Serial No. 255,213.

To all whom it may concern:

Be it known that I, HECTOR P. MACLAGAN, a citizen of the United States, residing at Park Ridge, in the county of Cook 5 and State of Illinois, have invented a certain new and useful Improvement in X-Ray Cones, of which the following is a specification.

My invention relates to protective cones 10 employed in X-ray work for preventing the X-rays from acting upon undesired parts and more specifically my invention relates to such cones employed in connection with the making of radiographs of the mouth 15 and teeth. For this use it has been found difficult to hold the protective cone in the desired place on the face of the patient on account of the irregular conformation of the face. For example, after the operator 20 has properly placed the cone and before the exposure could be made, the patient, having nothing to indicate to him the desired position in which to hold his head, easily moves its slightly and thus throws the apparatus 25 out of its proper relation to the part being radiographed. My invention avoids this difficulty by providing in connection with the cone, guides or supports to engage the face of the patient, which supports are ad- 30 justable to firmly engage any part of the face for any desired angle of the axis of the cone.

My invention will best be understood by reference to the accompanying drawings 35 showing a preferred embodiment thereof, in which—

Figure 1 is a plan view of my improved cone and

Fig. 2 shows the cone in side elevation and 40 partially in section.

Similar numerals refer to similar parts throughout the several views.

As shown in the drawings, the device consists of sheet of metal 10, in the form of a 45 frustum of a cone, this part being of any suitable material such as brass to give strength and stability to the device. A flange 11, annular in form, is attached to the part 10 to facilitate supporting the cone from a standard. On the inner surface of the part 10 a protective lining 12 of suitable material such as lead, is provided to prevent the X-rays from acting upon parts not

desired. The lead is folded over the edges of the sheet 10 as indicated to hold it in place.

At three equidistant points around the outer surface of the sheet 10 and midway between its ends, posts 13 are secured to said sheet and carry clamping screws 14 for holding rods 15, which are slidably mounted in said posts substantially parallel with the sides of the cone, in any adjustment it is desired to give said rods to properly locate said cone relatively to the face of the patient. The rods are preferably of insulating material such for example as hard rubber to protect the patient from shock resulting from any electric charge that may find its way to the cone.

In using my improved cone, it is supported by any convenient standard as is common in the art, and adjusted relatively to the face of the patient so that the X-rays passing through it will be applied to the place to be radiographed. The rods 15 are then adjusted to rest at their outer ends against the face of the patient, in which position they are securely held by the screws 14. This affords the patient a positive indication of the position in which the head is to be held and to a certain extent supports the head in that position, thus reducing to a minimum the danger that the patient will move from the proper position between the time that the apparatus is given the desired adjustment and the end of the exposure of the dry plate.

The flange 11 is provided with opposite notches 16 in its outer edge to facilitate locating it upon and securing it to the supporting mechanism.

In carrying out my invention, I do not limit myself to the use of three rods 15 as I may employ any other convenient number, 95 nor do I limit myself to using my improved device upon the face, as it is equally effective in any connection where small areas are to be treated and ordinary compression devices cannot, from the nature of the part, 100 be used. I may employ therefore any equivalents known to the art at the time of the filing of this application without departing from the scope of the appended claims.

From the above it will be understood that 105 my invention provides a means for project

ing the X-rays at any desired angle to the surface treated and at the same time engaging said surface with the rods or compression members referred to; for said members are independently movable so that their ends may conform to any irregular surface at whatever angle the X-rays may be projected. Any desired devices may be employed instead of the rods referred to, the only requisite being that they shall, to realize my invention, be capable of such movement and adjustment that their outer ends may engage an irregular surface for any desired angle of projection of the X-rays against said surface.

What I claim is:

1. In combination, a tubular shield for the local application of X-rays, and rods projecting from the end of said shield for engaging the surface treated.

2. In combination, a tubular shield for the local application of X-rays, rods slidably carried by said shield for engaging the surface treated, and clamping screws for holding said rods in any desired adjustment.

3. In combination, a conical tubular shield for the local application of X-rays, posts carried by said shield, and rods of insulating material adjustably mounted in said posts to engage the surface treated.

4. In combination, a conical tubular X-ray shield, posts projecting outwardly from said shield, and rods of insulating material adjustably mounted in said posts substantially

parallel with the outer surface of said shield to engage the surface treated.

5. In combination, a conical tubular X-ray shield, posts carried on the outer surface of said shield, rods of insulating material slidably mounted in said posts substantially parallel with the outer surface of said shield to engage the surface treated, and clamping screws in said posts for holding said rods in any desired adjustment.

6. In combination, a tubular X-ray shield, and members associated with said shield and capable of independent movement to engage an irregular treated surface, whereby in treating said surface the X-rays may be given any desired angle relatively to said surface and said members may be moved to engage said surface for said angle of application of the X-rays.

7. In combination, a tubular X-ray shield, members associated with said shield and capable of independent movement to engage an irregular treated surface, and means for clamping said members in any position of adjustment, whereby in treating said surface the X-rays may be given any desired angle relatively to said surface and said members may be moved to engage said surface for said angle of application of the X-rays and clamped in said engaging position.

It witness whereof I hereunto subscribe my name this 16th day of September, A. D. 1918.

HECTOR P. MACLAGAN.
